George W. Dickens Inventor

By John D. Miller

Attorney

UNITED STATES PATENT OFFICE.

GEORGE W. DICKENS, OF COLUMBUS, OHIO.

WEDGE.

Application filed December 12, 1921. Serial No. 521,869.

To all whom it may concern:

Be it known that I, GEORGE W. DICKENS, a citizen of the United States, residing at Columbus, in the county of Franklin and 5 State of Ohio, have invented certain new and useful Improvements in Wedges, of which the following is a specification.

This invention relates to new and useful improvements in wedges and more especially 10 to a wedge employed in raising locomotives off the rails in making repairs.

One of the principal objects of my invention is to provide a wedge of the above character with a special guard or flange which 15 will engage or embrace the rail and securely hold the wedge in place while the necessary repairs are being made, thereby not only facilitating the work but preventing liability of injury to the workmen and others, as 20 will more fully hereinafter appear.

In the accompanying drawings, which are for illustrative purposes only and are therefore not drawn to scale:-

Fig. 1 is an inside side elevation, illustrating the application of my invention, one wheel of the locomotive being shown in dotted lines.

Fig. 2 is an outside elevation of the wedge and rail.

Fig. 3 is an end view, the rail shown in section and Fig. 4 is a detail perspective view of the wedge.

Referring to the drawings for a more particular description of my invention, and in 35 which drawings like parts are designated by like reference characters throughout the several views, the numeral 1 represents the rail, 2 one wheel of the locomotive and 3 my improved wedge, as a whole.

The wedge comprises a longitudinal bar 4 of rectangular form in cross section which fits on top of the rail and supports or elevates one wheel of the locomotive above the same in making repairs. The top of this 45 bar is beveled or tapered downwardly at one end, as 5, to form a wedge 6, which facilitates the raising of the locomotive wheel, as will be apparent.

In carrying out my invention, the bar 4 is provided at one edge and preferably for 50 the greater portion of its length, with an offset depending guard 7 which embraces the inner edge of the rail head, said guard being

formed at its bottom edge with an outwardly extending right-angularly bent flange 8 55 which closely fits or engages the bottom wall 9 of the rail head and in conjunction with the guard, holds the wedge securely in place while making repairs.

It is a well known fact to those skilled 60 in the art to which this invention appertains, that wedges are used in railroad yards in place of a jack to raise locomotives off the rails in order to make repairs. In fact, on the larger types of locomotives, especially 65 that known as the "Mallet" type, jacks cannot be used at all for making certain repairs. The wedge now in use, however, frequently slips off the rail, which not only causes damage to the engine and delays the work, but 70 is exceedingly dangerous to the workmen since there is danger of them becoming crushed beneath the locomotive when the wedge slips. Further, the wedge often flies several feet and weighing about 100 pounds, 75 is apt to cause injury should it strike a workman.

Through the use of my invention, however, liability of the wedge slipping from place is safeguarded, and hence, not only are 80 delays in making repairs obviated, but danger to the workmen for the above reason is removed.

From the foregoing description taken in connection with the drawings, it is thought 85 that the construction, operation and advantages of my invention will be readily understood without requiring a more extended explanation.

Having described my invention, what I 90 claim as new and desire to secure by Letters Patent, is:-

A wedge adapted to be used for elevating a wheel with relation to a rail, comprising a block which is rectangular in cross section and which is beveled at one end portion, said block having at one side corner an outstanding offset portion the upper edge of which is spaced from the upper face of the block, said offset portion being provided at 95 its lower edge with an inwardly disposed flange adapted to engage under the head of the rail.

In testimony whereof I affix my signature.

GEORGE W. DICKENS.
